UNITED STATES PATENT OFFICE.

SARAH E. GRIGGS, OF WOODLAND, CALIFORNIA.

DESIGN FOR A HAT-HOLDER.

SPECIFICATION forming part of Design No. 30,463, dated April 4, 1899.

Application filed February 20, 1899. Serial No. 706,274. Term of patent 14 years.

To all whom it may concern:

Be it known that I, SARAH E. GRIGGS, a citizen of the United States, residing at Woodland, county of Yolo, State of California, have 5 invented and produced a new and original Design for a Hat-Holder, of which the following is a specification, reference being had to the accompanying drawing, forming a part thereof.

The single figure is a view of my device.

10 My design comprises a rectangular fork A, formed of wires twisted together, and the two arms A' of the fork join in the center in a stem B, extending downwardly at right angles from the fork, the twisted wires of which 15 the stem is formed being coiled to form an inverted conical cup C at the bottom of the stem. The two arms of the fork extend upwardly approximately parallel at a distance

apart, and at the top the twisted wires which form these arms are separated and bent, so 20 as to form rectangular heads D, which have their greatest length horizontally and are made concavo-convex, as shown. The outer sides of the upper bars of these arms are serrated, as shown at d.

25 Having thus described my invention, what I claim as new, and desire to secure by Letters Patent, is—

The design for a hat-holder substantially as shown and described.

30 In witness whereof I have hereunto set my hand.

SARAH E. GRIGGS.
